UNITED STATES PATENT OFFICE.

ANNIE K. WILKINS, OF PITTSBURG, PENNSYLVANIA, ADMINISTRATRIX OF HENRY WILKINS, DECEASED.

SMOKE-CONSUMER.

SPECIFICATION forming part of Letters Patent No. 746,426, dated December 8, 1903.

Application filed January 19, 1903. Serial No. 139,640. (No model.)

To all whom it may concern:

Be it known that I, ANNIE K. WILKINS, a citizen of the United States, and a resident of Pittsburg, in the county of Allegheny and State of Pennsylvania, administratrix of the estate of HENRY WILKINS, deceased, late a citizen of the United States and a resident of Allegheny, in the county of Allegheny and State of Pennsylvania, as by reference to the duly-certified copy of letters of administration hereto annexed will more fully appear, who did in his lifetime invent certain new and useful Improvements in Smoke-Consumers, do hereby declare the following to be a full, clear, and exact description of said invention.

This invention relates to means for feeding air and steam to boiler-furnaces; and the object in view is the provision of means to supply a heated current of air and steam into the escaping products of combustion, to thereby effect the consumption of carbon in the smoke and to promote the combustion of the gases, to the end that fuel will be saved and more perfect combustion will be attained.

The improved device is situated in rear of the usual bridge-wall of the furnace, so as to be partially protected thereby from the bed of incandescent fuel on the grate, and said device is adapted to discharge the current in an upwardly and rearwardly inclined direction, so as to obtain an intimate commingling of the injected aerated mixture with the gaseous products of combustion.

The device may be used advantageously on steamships for ventilating the holds thereof by drawing out the foul or impure atmosphere.

With these ends in view the invention consists in the construction, combination, and arrangement of parts, which will be herein-after fully described and claimed.

Reference is to be had to the accompanying drawings, forming a part of this specification, in which similar characters of reference indicate corresponding parts in both figures.

Figure 1 is a longitudinal sectional elevation through a part of an ordinary steam-boiler furnace, illustrating the application of the improved means for injecting aerated mixture into the escaping products of com-

bustion. Fig. 2 is a sectional elevation in the plane indicated by the dotted line 2 2 of Fig. 1.

The ordinary boiler-setting 5 includes the bridge-wall 6, which is located in rear of the grate 7 and below the boiler 8, the flame passage or flue 9 lying between the top of the bridge-wall and the bottom of the boiler.

A means for injecting the aerated mixture 60 is situated transversely across the furnace and in rear of the bridge-wall 6. This distributing means consists of a distributing cylinder or shell 10, a combining and air-feeding tube 11, and an injector-pipe 12. The 65 casing or cylinder 10 extends across the flue or passage 9, and its end portions are supported in the side wall of the boiler-setting, as shown more clearly by Fig. 2. The ends of this cylinder or casing are closed either by 70 the provision of suitable heads or by the side walls of the setting, and this cylinder is provided with one or more slots 13^a. As shown by Fig. 1, the slot or slots 13^a open radially through the rear portion of the casing, so as to discharge the aerated mixture 75 in an upward and rearward path, and thereby secure an intimate commingling of the steam and air with the gaseous products of combustion, an aerated mixture being injected into the escaping products of combustion substantially in the direction of the course pursued by said products of combustion.

The combining-tube 11 is of less diameter than the casing or cylinder 10, and this combining-tube is disposed in a concentric position within said cylinder, thus leaving a surrounding space or chamber between the tube and the cylinder. The combining-tube 11 is not as long as the casing 10, and this tube 80 has two open ends, which communicate with the opposite end portions of the distributing-casing. Within the combining-tube is arranged an injector-pipe 12, the latter being somewhat shorter than the combining-tube 95 and arranged centrally therein. The injector-tube is provided at its end portions with nozzles 13, which lie within the open end portions of the combining-tube 11 and are arranged to face in opposite directions, so as to discharge 100 jets of steam through both ends of the combining-tube.

Air is supplied to the combining-tube 11 by means of a pipe 14, which is shown by Fig. 2 as entering the lower part of the furnace and as having an upstanding branch 15, 5 which passes through the middle portion of the casing 10 and is united to the under side of the combining-tube 11 at a point between the open ends thereof. The end portion of the air-supply pipe 14 may terminate just 10 outside of the boiler-setting in order that atmospheric air may flow through the pipe freely; but this end of the pipe 14 may be carried to any place from whence it is desired to draw the supply of air—as, for example, to 15 the hold of a vessel.

Steam is conveyed to the injector-tube 12 by means of a pipe 16, which extends through the air-supply pipe 14 and is provided with an upstanding branch 17, the latter passing 20 through the branch 15 of the air-pipe and coupled to the injector-tube 12 at a point between the nozzles 13 thereof. This steam-pipe is also provided with an upstanding branch 18, which is shown as having communication with the steam-drum of a boiler, and 25 said branch pipe 18 is provided with a suitable cock or valve 19, which controls the passage of steam from the boiler to the injector-tube.

30 The described arrangement provides for the uniform distribution of the commingled air and steam into the end portions of the distributing-cylinder, and this commingled current is adapted to be heated before it is

discharged into the escaping products of 35 combustion.

Having thus described the invention, what is claimed as new, and desired to be secured by Letters Patent, is—

In a smoke-consuming furnace, the combination of a casing provided with closed ends and with a rearwardly-facing outlet-opening, a combining-tube arranged centrally in said casing, said tube being open at its ends and terminating at points close to 40 the closed ends of the casing, an air-pipe connected to and communicating with the middle portion of the combining-tube and extending through the casing, an injector-pipe disposed lengthwise within the combining-tube and having oppositely-facing jet-nozzles which lie within the open ends of said tube, and a steam-pressure pipe connected to the injector-tube at a point between the nozzles thereof, the arrangement being such that air 45 passing into the combining-tube is caused to flow in two currents by the suction created by the jets emerging from the oppositely-facing nozzles.

In testimony whereof I have signed my 50 name to this specification in the presence of two subscribing witnesses.

ANNIE K. WILKINS,
Administratrix of the estate of Henry Wilkins, deceased.
